[57] CLAIM

The ornamental design for a fuel pump anti-tamper enclosure, as shown and described.

DESCRIPTION

FIG. 1 is a right side elevation view of a fuel pump anti-tamper enclosure which has separable upper and lower sections, showing our new design;

FIG. 2 is a front elevation view thereof;

FIG. 3 is a bottom plan view thereof;

FIG. 4 is a left side elevation view thereof;

FIG. 5 is a rear elevation view thereof;

FIG. 6 is a top plan view thereof;

FIG. 7 is a greatly enlarged top perspective view of the interior of the bottom section thereof;

FIG. 8 is a greatly enlarged bottom perspective view of the interior of the top section thereof;

FIG. 9 is an enlarged top plan view of the interior of the bottom section thereof;

FIG. 10 is an enlarged bottom plan view of the interior of the top section thereof;

FIG. 11 is an enlarged perspective view from the upper left rear thereof; and

FIG. 12 is a greatly enlarged section view along the line 12—12 of FIG. 1.
